UNITED STATES PATENT OFFICE

103,383

DESIGN FOR AN ENCLOSED CAB FOR POWER SHOVELS OR SIMILAR DEVICES

George S. Lawson, Cleveland, Ohio, assignor to
The Byers Machine Company, Ravenna, Ohio,
a corporation of Ohio

Application April 6, 1936, Serial No. 61,973

Term of patent 14 years

To all whom it may concern:

Be it known that I, George S. Lawson, a citizen of the United States and a resident of Ravenna, county of Portage, and State of Ohio, have invented a new, original, and ornamental Design for Enclosed Cab for Power Shovels or Similar Devices, of which the following is a specification, reference being had to the accompanying drawings forming a part thereof.

In said annexed drawings:—

Fig. 1 is a plan view of my enclosed cab for power shovels or similar device;

Fig. 2 is a side elevation of the same;
Fig. 3 is a rear elevation; and
Figs. 4 and 5 are opposite prospective views taken from the front.

What I claim is:

The ornamental design for an enclosed cab for power shovels or similar devices substantially as shown.

GEORGE S. LAWSON.
